UNITED STATES PATENT OFFICE

CHARLES F. SPARKS, OF ST. LOUIS, MISSOURI

BAG TURNING APPARATUS

Application filed July 25, 1928. Serial No. 295,262.

This invention relates to bag turning apparatus and with regard to certain more specific features, to bag turners of an automatic type.

5 Among the several objects of the invention may be noted the provision of an improved and simplified form of automatic bag turner in which a spreading action is caused to accompany the turning action, whereby 10 the bags are simultaneously advantageously flattened; the provision of a bag turner of the class described in which the relative travel between certain turning and holding elements is so distributed among said ele- 15 ments moving in an opposed manner, that the maximum absolute travel of each of said elements is less than the length of a bag; the provision of a bag turner of the class de- 20 scribed having automatic positioning means for placing bags in positions to be turned and an automatic release from said holding means after turning is completed and the provision of a device of the class described of 25 maximum simplicity and ruggedness of construction but having a minimum of space requirement. Other objects will be in part obvious and in part pointed out hereinafter.

The invention accordingly comprises the elements and combinations of elements, features of construction, and arrangements of parts, steps and sequence of steps, which will be exemplified in the structure hereinafter described, and the scope of the application of which will be indicated in the following 35 claims.

In the accompanying drawings, in which is illustrated one of various possible embodiments of the invention,

40 Fig. 1 is a side elevation of the machine shown with a bag positioned ready for turning;

Fig. 2 is a front elevation of Fig. 1, certain supporting members for bags being shown broken away;

Fig. 3 is a fragmentary view similar to Fig. 2 but showing the position of a bag immediately after it has been turned by certain turning sticks;

Fig. 4 is a fragmentary side elevation, similar to Fig. 1 but showing the position of a

bag immediately after it has been turned and prior to delivery thereof, as in Fig. 3;

Fig. 5 is a top plan view of the machine shown in its Fig. 4 position, wherein the machine is ready to deliver a bag but the bag being omitted in Fig. 5;

Fig. 6 is a fragmentary side elevation, similar to Fig. 1, showing a modified form of the invention;

Fig. 7 is a fragmentary side elevation similar to Fig. 6 showing an alternate position of the modified form; and

Fig. 8 is a plan view of the right end portion of Fig. 6.

Similar reference characters indicate corresponding parts throughout the several views of the drawings.

Referring now more particularly to Fig. 1, there is illustrated at numeral 1, a frame comprising four vertical corner posts 3 fastened together at their tops and bottoms by cross pieces 5 and centrally by cross supports 7, said central cross supports carrying a yoke 9 for supporting a main shaft 11 and a jack shaft 13. Power is delivered to the machine by means of a pulley and belt combination 15 associated with said jack shaft 13, the jack shaft being geared with the main shaft 11 by way of a pinion 17 and meshed gear 19, the latter gear being located on the main shaft. 80

The gear 19 also comprises a crank disc carrying a crank pin 21 to which is adjustably fastened by a nut 22, an eccentric crank 23, said eccentric crank being normally movable as one with the crank disc and gear 19 and having on its outer end a second crank pin 25. From the above it will be seen that the position of the second crank pin 25 is adjustable with respect to the first fixed crank pin 21, the purpose of the eccentric crank 23 being to provide this adjustment. In effect the crank pins 21, 25 are crank pin extensions from the crank disc 19, thereby forming a double opposed crank mechanism.

The crank pin 21 is coupled to an upper connecting rod 27 and the crank pin 25 is coupled to a lower connecting rod 29. The upper connecting rod 27 controls the oscillating or reciprocatory action of an upper quadric linkage or upper swinging frame 31.

and lower connecting rod 29 controls the opposed oscillating or reciprocatory action of a lower parallel linkage or lower swinging frame 33, each connecting rod being joined with its linkage by means of a pin coupling 35.

The lower swinging frame 33 comprises two preferably parallel arms 37 pinned to each of the rear corner posts 3 and joined at their outer ends by a connecting link 39 to form a parallel linkage on each side of the machine, said parallel linkage being joined by a pivot shaft 41 and two guide rods or rollers 43, the guide rods 43 being located somewhat above the pivot shaft 41. The pivot shaft carries pivotally thereon connecting pieces 45 having right angular pivot pins 47, whereby a universally movable support is provided for each of a pair of downwardly located, ball-end turning sticks 49, said sticks passing between and being partially guided by the guide rods 43. The turning sticks 49 are further guided by means of a pair of guide pulleys 51 and yokes 53 held in supporting pieces 55, the latter being held on another supporting rod 57. The guides 51, 53, 55 (taken as a whole) are adjustably mounted on the shaft 57 (see set screws 58) but in operation are rigid as to cross movement. The turning sticks 49 are each given the double curved shape shown best in Figs. 2 and 3 by means of which said sticks upon rising are given a spreading movement at the upper ends thereof as will be clear by examination of said Figs. 2 and 3. The rising action of the sticks, as well as falling action thereof, is effected by the oscillating or reciprocatory action of the lower swinging frame 33 under action of the connecting rod 29 and its revolving crank pin 25. It will be noted that if the guides are adjusted at a greater width than the pivot points of the lower ends of the turning sticks, that the upward movement of a pair of straight turning sticks will cause the points or ball ends thereof to swing outwardly in the direction of the width of the bag as in the case of the curved turning sticks above described, this comprising an alternative form.

The upper swinging frame 31 comprises two arms 59, one pinned to each of the rear corner posts 3. These arms 59 are joined at their forward ends by the rod 63 upon which are held outer holding sticks 65. Spaced from the rod 63 is another rod 67, the distance between the rods 63 and 67 being such as to provide just enough space between them to permit sliding movement of the turning sticks 49 therebetween and the turning of the bag therethrough. The inner holding sticks 69 rock with said rod 67 in the swinging frame 31, the rod 67 being provided with a crank 71 which is normally held in the position shown in (Fig. 4) by

means of a spring 73, thus normally holding the sticks or arms away from each other. Control of the action of the inner swinging holding sticks 69 is had by a bridle link 75 pivoted to one of said posts 3, said link 75 having a slot 77 therein engaged by a pin 79 mounted on the crank 71. Hence as the upper swinging frame 31 moves up and down, the pin 79 moves in the slot 77 which itself will be caused to swing with the swinging link 75. The length of the slot 77 is so arranged that for a certain fraction of the oscillation, the pin 79 rides freely therein, but when a pre-determined descent has been effected on the down stroke of the frame 31, then the pin 79 engages with the left-hand end of the slot 77 so that the swinging holding sticks 69 are moved counterclockwise, the spring 73 providing the necessary resiliency and tending to normally hold the holding sticks 65, 69 apart or in open position, that is, until abnormally acted upon at the end of the slot 77. The purpose of the abnormal action in bringing the holding sticks together at a predetermined descent is to cause them to more readily enter the mouth of a bag, as will be seen hereinafter.

After entry of the holding sticks into the bag mouth it is again desirable that they approach slightly at the end of the stroke and for this purpose there is provided a second bridle link 81 having a slot 83 engaging with a pin 85 located on a second crank 87, the crank 87 being fastened to said pivotal cross rod 67. By this means, as illustrated in Fig. 4, when the end of the stroke is reached, the pin 85 engages the rear end of slot 83 thus slightly pushing the holding sticks together just sufficiently to relieve the tension on the open end of the bag, in order that the bag may be pulled off from the holding sticks by the lower turning sticks 49 without too much friction.

In order that the control of the holding sticks may be more effective, the forwardly located sticks 65 are also given a lateral movement. In order to accomplish this, the shaft 63 is provided with a crank 64 reaching downwardly and carrying a lower pin 66, similar to the pin 85. A third bridle link 68 is pivoted to the rear upright 3 and is provided with a connection with the pin 66, but this connection is not a slotted one. It is an ordinary pin connection. The proportions of the parts just described are so chosen that the sticks 65 swing inwardly more at the top end of the stroke than they do at the bottom end of the stroke thereby more readily entering the bag mouth upon descent, as well as assisting in positioning the holding of the bag at the most favorable position for turning by the turning points of the turning sticks.

Adjustably mounted on a cross shaft 89 in the main frame 1 are two pulleys 91. 130

Mounted ahead of these pulleys and engaging them are a pair of similar pulleys 93 located on a cross shaft 95, the latter shaft 95 being swung from supports 97 of a jack shaft 99. The jack shaft has another crank 101, retracted by a spring 103 so as to cause said pulleys 99 to be held against the pulleys 91. These two pairs of pulleys are so positioned in the turning machine that as the 10 turning sticks push the bottom of the bag to their fullest upward stroke they will push the bottom of the turned bag directly in between these two pairs of pulleys, which by revolution will cause the bag to be drawn upward and through them while the turning sticks descend downward out of the bag.

A delivery pulley 105 serves to receive bags from the pulleys 91 and deliver them from the machine and out over an oscillating set of fly leaves 107. Synchronized mechanism for operating the fly leaves 107 to throw off the bags is not shown, because such synchronized devices are well known and would merely serve to complicate the 25 description herein. An idler pulley 109 serves to force the bags against the delivery pulley 105 for ejection purposes. The pulleys 91, 105 are driven to perform the above functions by means of a crossed belt 109 shown more particularly in Figs. 1, 2 and 5.

Delivery of bags to the turning sticks is effected by providing a forwardly located table 111 upon which the bags are placed in an orderly stack. The lower parts of the bags, 35 as illustrated, lie more or less up and down, while the upper ends rest upon a lateral back-board 113. Directly above and in front of the bags are supported a pair of resiliently mounted bag opening guides 115. Each 40 guide 115 comprises a more or less sidewardly tapered flat plate mounted on a stem 117 and associated with a spring 119 such that the spring tends normally to place the guides 115 against a set of limiting stops in the 45 spread out Fig. 5 position. Thus provision is made whereby an operator may pick a closed bag and pull its mouth over the wedge shaped plates or guides 115 which are drawn in against the resilient action of springs 119 so that when the bag is released by the operator it is held in stretched open position.

The angular positions of the bags in the stack as shown in Fig. 1 and described above is believed to be new and has the advantage 55 that the upper end of each bag may be moved for opening the top of the same and placing it on the guides 115 without moving the lower end of the bag, but thereby exposing the mouth end of the next bag for an operator to get to it. This gives the operator, or any automatic machine which may be used to perform this action, much less work to do and movement to accomplish.

In order to automatically deliver the bags 60 from their positions over the guides 115,

there is provided a swinging feed mechanism comprising a parallel mechanism 121 swung from an extending arm 123, at the lower end of which is provided one pair of fixed fingers 125 on a cross shaft 127. Pivoted on 70 said cross shaft 127 is a set of resiliently mounted fingers 129, normally pressed by springs 131 in a counterclockwise direction. (Figs. 1 and 4.)

Oscillating action of the parallel mechanism 121 is controlled by the linkage comprising links 133, 135, 137, connecting said linkage with one of the links 59 of the upper swinging frame 31. When the parallel mechanism 121 is in its outward position 80 (Fig. 4), the resiliently mounted fingers 129 engage a cross plate 139 on which said guides 115 are mounted. This engagement results in relative clockwise movement of the resilient fingers 129 after they have passed over 85 the bag so that upon return movement they will enter the mouth of said bag. The fixed fingers 125 also pass over the bag, the stretched mouth of the bag springing aside enough to permit the action. As illustrated 90 in Figs. 1 and 4, the lower ends of the fixed fingers 125 are bent downwardly to facilitate entry into the bag mouth. As the parallelogram 121 swings back the fingers 125, 129 automatically spring apart to hold the bag, 95 and to take it from the guides 115 and deliver it to a position over the lower sticks 49 and below the upper sticks 65, 69 as shown by the dotted lines in Fig. 1. It is clear that inasmuch as the mouth of the bag is held 100 open at four rectangularly located points, that the shape of the open mouths of the bags will be rectangular. Upon return of the fingers 125, 129 for another bag, the resilient action of fingers 125 and of the edge of the bag itself permits said fingers to pass out of the bag mouth while the holding arms or sticks 65, 69 hold the bag and take it down, 105 the turning sticks 49 at the same time rising.

The next action is the rising of the lower sticks and the descent of the upper sticks, whereby the bag is turned from the Fig. 1 position to the Fig. 4 position, the fingers 125, 110 129 in the meantime returning for another bag which has been placed upon the guides 115 by an operator.

Immediately after the period of arrangement of parts shown in Fig. 1, the upper holding sticks will be caused to approach one another just before entering the bag mouth. 115 Thereafter they will separate, because the left hand end of slot 77 recedes to the left due to its swinging action, thereby permitting the spring 73 to contract and pull open the holding sticks. Fig. 4 illustrates this, except that in that figure the movement has proceeded to a point where the second bridle link 81 has come into play so as to again stretch the spring 73 and cause a slight reclosing of the holding sticks, so that as a 120 125 130

last part of the stroke of the lower sticks 49 is effected, the turned bag is released from said holding sticks and delivered in between the rolls or pulleys 93, 91 to be delivered out 6 through rolls 105, 109.

- It will be seen that by means of the opposed action between the upper and lower swinging frames and their respective sticks or arms, that maximum relative movement is 10 effected with minimum absolute movement of each. This results in a shorter and more compact machine, because the crank throw of pins 21, 25 needs be only one half as long as if all the movement were applied to one 15 frame or set of sticks or arms. The parallelogram-frame mountings for the turning and holding sticks or arms provide simplified means without sliding pairs for maintaining substantial parallelism between the sticks. 20 In the above, a manual method has been described for placing the bags over the spreaders 115. Automatic means may also be used, such as illustrated in Figs. 6 to 8. In this modification a table 111 is provided 25 with the described means including the element 113 for holding the bags with their upper portions lying laterally. The cross support 139 pivotally carries said spreaders 115, said spreaders having tail pieces 150 held 30 together by a tension spring 152 such that the normal tendency of the spreaders is to separate. However, cranks 154 fastened to the lower ends of the pivot pins 117 of the spreaders and coupled to a cross head 156 by 35 means of connecting rods 158, prevent the normal spreading action of the spring 152 from taking place. The cross head 156 is operated to reciprocate by means of a connecting rod 160 having a lost-motion engagement with a rocker arm 162, the latter having a lost-motion engagement with the connecting rod 164 which is operated from said 40 oscillating pieces 59 of the oscillating frame 31 by means of an extension 166. It will be comprehended that as the frame 31 moves 45 up and down that the described mechanism causes the spreaders 115 to open and close. They spread apart or open when the frame 31 descends for turning a prior bag, and they 50 return to closed position when the frame 31 again rises. (See Fig. 6.)

In order to place the mouth of a bag in open position for entry of the spreaders 115 therein, there is pivoted to the same pivot pin 55 as rocker 162, a goose neck 168 which, however, is not oscillable directly with said rocker 162 but only indirectly in the following manner:

The outer end of the goose neck 168 comprises one fixed jaw 170 of a pair of pinchers, the other jaw 172 thereof being swingable with respect to said fixed or main jaw 170. The tail end of the movable jaw 172 is linked to the rocker 162 by means of a connecting rod 174. An adjustable stop 176

limits or determines the movement of the movable jaw 172 in opening with respect to the fixed jaw 170. The ends of the pinchers are roughened as by knurling or scarifying.

From the above it will be seen that the mechanism in proceeding to its Fig. 6 position, by means of the connecting rod 174, causes the movable jaw 172 to open only after the goose neck 168 swings down. The jaws proceed to a position such that they rest upon 75 the stack of bags.

As the upper frame 31 descends and the rocker 162 is moved outwardly to the Fig. 7 position, the next action in regard to the pinchers is a closing movement of the movable jaw 172. Inasmuch as the two jaws 170, 172 merely rest upon the stack of bags and are made rough, the result is first a wrinkling up of a layer of cloth on the top side only of the topmost bag which is frictionally 80 pinched by said jaws as they close. After the jaws are closed completely on the pinched cloth, their further relative movement is prevented, whereupon the action of the connecting rod 174 is to pick up the goose neck 85 168 as illustrated in Fig. 7. This means that one side of the bag is still lying on the stack and the other is picked up so that the mouth thereof is opened ahead of the then closed spreaders 115. The action is so synchronized, as illustrated in Figs. 6, 8, that after the one side of the bag has been lifted the predetermined distance the spreaders spring outwardly to pass into the mouth of the bag 90 and grip the bag for the purpose of delivering the bag to the turning stick, that is, by means of the fingers 125, 129 as hereinbefore described. The action of the spreaders in spreading the bag is to pull the gripped wrinkle of cloth from between the jaws 170, 172 95 and hold the bag for further action by the fingers 125, 129.

The purpose of the lost-motion engagements between the links 160, 164 and the rocker 162 is to provide means whereby the 100 pinchers will be accommodated to various stack heights.

In view of the above, it will be seen that the several objects of the invention are 105 achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. In bag turning apparatus, reciprocatory means carrying pivoted sticks adapted to turn bags, means for supporting and guiding said sticks, said sticks being curved so as to provide a predetermined movement thereof 130

through the guiding means while turning the bags.

2. In bag turning apparatus, reciprocatory means, means for adjustably pivoting sticks thereto, said sticks being adapted to turn bags, means for supporting and guiding said sticks, said sticks having a predetermined curvature so that said guiding means will cause them to spread as bags are turned.

3. In bag turning apparatus, turning means having reciprocatory movement, holding means also having reciprocatory movement, said two movements of the turning and holding means being opposed, whereby enough relative movement is effected between said means for turning a bag but the absolute movement of each means is less than the length of the bag, said opposed movements being effected by a double opposed crank and connecting linkages.

4. In bag turning apparatus, turning means having reciprocatory movement, holding means also having reciprocatory movement, said two movements of the turning and holding means being opposed, linkages for mounting the turning and holding means respectively, a double opposed crank, and connecting rods from said crank to said linkages.

5. In bag turning apparatus, turning means having reciprocatory movement, holding means also having reciprocatory movement, said two movements of the turning and holding means being opposed, whereby enough relative movement is effected between said means for turning a bag but the absolute movement of each means is less than the length of the bag, means for taking a bag from the turning and holding means after turning has been accomplished and delivering it from the machine, said holding means being adapted to release the bag as turning is completed and automatic means for taking a bag from a supply and positioning it so as to be acted upon by said holding and turning means.

6. In bag turning apparatus, turning means having reciprocatory movement, holding means also having reciprocatory movement, said two movements of the turning and holding means being opposed, whereby enough relative movement is effected between said means for turning a bag but the absolute movement of each means is less than the length of the bag, means for taking a bag from the turning and holding means after turning has been accomplished and delivering it from the machine, said holding means being adapted to release the bag as turning is completed and automatic means for taking a bag from a supply and positioning it with open mouth between the ends of the holding and turning means, said holding and turning means passing through the bag mouth from above and below respectively, the turn-

ing means passing between the holding means and up to said delivery means.

7. In bag turning apparatus, means for automatically opening a bag comprising means for supporting the bag, a swingable main jaw adapted to approach and recede from the bag, a second jaw movable on the main jaw, a rocker, a connecting rod between the rocker and said second jaw, whereby the jaws open automatically only after movement of the main jaw toward the bag surface has been completed and whereby receding movement away from the bag surface can start only after pinching movement of said jaws has been completed.

8. In bag turning apparatus, means for automatically opening a bag comprising means for supporting the bag, a swingable main jaw adapted to approach and recede from the bag, a second jaw movable on the main jaw, and a linkage in normal operation preventing movement of the second jaw with respect to the main jaw until the main jaw has descended upon the bag, and preventing lifting of the main jaw from the bag until relative movement of the jaws has ceased.

9. In bag handling apparatus, means for supporting a stack of bags, pinchers, means for applying the pinchers to the bags consecutively, and a linkage in normal operation causing the pinchers to pinch up a portion of the topmost bag, preventing pinching action during application movement of the pinchers as a whole, and preventing lifting movement until pinching has been completed.

10. In bag turning apparatus, means for automatically opening a bag comprising means for supporting the bag, a swingable main jaw adapted to approach and recede from the bag, a second jaw movable on the main jaw, means for determining the movement of the second jaw with respect to the main jaw and a linkage in normal operation preventing movement of the second jaw with respect to the main jaw until the main jaw has descended upon the bag and preventing lifting of the main jaw from the bag until relative movement of the jaws has ceased.

In testimony whereof, I have signed my name to this specification this 9th day of July, 1928.

CHARLES F. SPARKS.
